UNITED STATES PATENT OFFICE.

ALFRED MARKS, OF LOMITA PARK, CALIFORNIA.

SAFETY TOILET-SEAT COVER.

Application filed February 3, 1922. Serial No. 533,988.

To all whom it may concern:

Be it known that I, ALFRED MARKS, a subject of the King of Great Britain, residing at Lomita Park, in the county of San Mateo 5 and State of California, have invented a new and useful Safety Toilet-Seat Cover, of which the following is a specification.

An object of this invention is to provide for hinged toilet seats, a practical cover that 10 will receive public favor, that can be vended in vending machines or otherwise conveniently supplied to toilets in other ways and which will protect the person from contact with the toilet seat both in the operation of 15 putting the cover on and in removing it from the seat as well as while in use.

A feature of the invention resides in that the paper sheet having the central orifice also has folded side flaps which serve as combined protectors for the hands in placing 20 the cover on the seat, and as retainers to fit upon the toilet bowl and to be clamped between the bowl and seat when the seat is in place for use.

Another feature of the invention includes 25 a flap extension at the front of the orifice of the sheet; extending part way toward the back of said orifice and temporarily held by connections arranged near the tip of the flap 30 and breakable by pressure of the seated person so that said flap is not in the way during vending or handling but becomes effective to protect against contact of the person with the front margins of seat orifice or bowl.

A further object of the invention is to provide 35 a toilet seat cover especially adapted for advertising purposes without exposing the advertising ink to the person of the user.

Other objects, advantages and features of 40 invention may appear from the accompanying drawing, the subjoined detail description and the appended claims.

The accompanying drawing illustrates the invention.

Figure 1 is a perspective view of a partly 45 lowered toilet seat with this invention applied thereto.

Fig. 2 is a transverse section looking forward 50 from the middle of the lowered seat after use and before removing the cover.

Fig. 3 is a plan of the under side of the cover ready to be grasped for application. Dotted lines indicate the fold creases.

Fig. 4 is a top view of the cover shown in 55 Fig. 3.

Fig. 5 shows the packet into which the cover is folded for distribution.

The seat body 1 has at its center an incipient elongate orifice 2, the rear portion *a* 60 of which is open and the front portion *b* outlined by two side slits *c*, *d* and temporarily closed by a tab 3 which is separated from the body 1 by the slits except at the permanent front connection 4 and breakable rear connections 5.

Said body terminates laterally in two side flaps 7 folded under the body 1 and adapted to afford means by which the person desiring to use the seat may take hold of the 70 edges of the seat to raise it, and which will rest on the top of the bowl to be gripped by the seat or the downwardly extending cushions usually thereon, so that when the seat is lowered, the cover will be held securely 75 in place.

The cover is preferably made of soluble paper of sufficient stiffness to hold its form, and the orifice is cut in part as indicated, and the side flaps 7 folded under.

Then the cover may be folded as desired. 80

The dotted lines 8, indicate lines along which the sheet may be folded to form the packet shown in Fig. 5.

In practice the packets may be carried in 85 the pocket, in travelling bags, in hand satchels or in other convenient ways so as to be available when needed for public toilet use; and they may be distributed by vending machines, or free to public toilets; and the tab or other parts of the cover may be 90 provided with advertising matter.

Preferably the advertising matter will be applied to those portions of the cover which will be visible in the folded packet and which will not come into contact with the 95 person of the user, and the cover is so folded as to simultaneously expose the outer surface *e* of the flaps 7, and the under surface *f* of the tab, so that the eye of the one who takes one of the covers may immediately fall 100 upon the advertisement.

In placing the seat cover in position for use the packet will be unfolded and grasped along the side flaps 7 which afford protection to the hands when raising the toilet 105 seat and placing the cover in position. The side flaps 7 are clamped between the bowl and the seat when the cover is in place and the seat is down and securely holds the cover 110 in position. The pressure of the seated per-

son breaks the rear connections 5 and the tab 3 falls downward and forward to protect against contact of the person with the front margins of the seat orifice or bowl.

5. An advantage is the ease and simplicity of application to a toilet seat and maximum protection against contact with the toilet seat or bowl.

10. A further advantage is that when the seat cover is in use the rear portion *a* of the orifice 2 being open and the tab 3 being disconnected by pressure of the seated person from the breakable rear connections 5 and such tab falling downward and forward affords a seat cover which not only gives maximum protection but provides a seat cover which affords maximum cleanliness and comfort to the user.

I claim.

20. 1. A toilet seat cover comprising a sheet having a centrally arranged incipient orifice and a tab outlined by slits and connected to the sheet at the front end of the orifice and lightly connected with the body of the sheet 25 at the rear portion, the connections at the rear portion of said tab being breakable by pressure of a seated person.

2. A toilet seat cover comprising a sheet provided with an incipient orifice in which 30 is a tab connected at one end with the body of the sheet and also lightly connected at its rear end with the body of the sheet, the connections at the rear end of the tab being breakable by pressure of a seated person; 35 said sheet being folded at its sides to form lateral flaps to be clamped between the seat and the toilet bowl and said sheet being folded so as to bring the underside of the

flaps and the tab into exposed position to form a closed packet upon which advertising matter may be presented to the eye simultaneously without being in position to contact with the body of the person using the toilet when the cover is in place.

3. A toilet seat cover comprising a sheet having an incipient elongate orifice the rear portion of which is open and the front portion of which is outlined by slits and temporarily closed by a tab; a permanent front connection and breakable rear connections connecting said tab to the sheet; and side flaps along the lateral sides of said sheet to protect the hand in applying the cover to a toilet seat and also to be clamped on the toilet seat when the seat is down and the cover on top of the seat; the rear connections connecting said tab to the seat being breakable by pressure of the seated person and said tab then affording protection to the seated person as set forth.

4. A sanitary seat cover comprising a blank having a body and an opening conforming to the opening in the seat except at its front portion where the blank has an inward extension connected at its front by a wide portion and at its rear corners by narrow strips to the main body but leaving the major part of the opening unobstructed, said extension forming an apron for the front of the seat when the narrow strips are torn in use by pressure of the body of the user.

In testimony whereof, I have hereunto set my hand at Los Angeles, California, this 26th day of January, 1922.

ALFRED MARKS.
